UNITED STATES PATENT OFFICE.

EWALD G. BAUM, OF NATICK, MASSACHUSETTS.

BOTTLE-CAP.

1,357,831.

Specification of Letters Patent.

Patented Nov. 2, 1920.

Application filed June 11, 1920. Serial No. 388,182.

To all whom it may concern:

Be it known that I, EWALD G. BAUM, a citizen of the United States, and a resident of Natick, in the county of Middlesex and 5 State of Massachusetts, have invented a new and Improved Bottle-Cap, of which the following is a full, clear, and exact description.

This invention relates to bottle caps and 10 particularly refers to an improvement in a cap or closure for milk bottles.

The invention contemplates the production of a thoroughly sanitary leak proof closure applicable to any standard milk bottle 15 to reduce the possibility of contamination of the contents to a minimum.

In creating this closure, particular attention has been paid to the formation of the mouth of standard milk bottles in order 20 that the cap will function properly therewith without the necessity of modifying in any way its present form.

An important feature of the closure resides in the multiplicity of points at which 25 it seals itself to the mouth when applied, thereby insuring to the consumer a clean, germ-proof staple, packaged to render the same impervious to dirt or filth.

A most serious objection to the form of 30 the caps now in use is due mainly to the fact that many consumers are prone to remove the cap by pressing it inward thereby permitting dust, dirt and other filth to commingle with the contents. The construction of this cap not only obviates but positively prevents the opening of the bottle by 35 this method.

Another important object featured by the 40 construction of this cap or closure is the facile manner with which it may be removed to prevent contamination from sediment adhering to its outer sides.

With the above recited and other objects 45 in view, some of which will be apparent from the following detailed description and claims when read in connection with the accompanying drawings, reference is made thereto in which;

Figure 1 is a vertical sectional view 50 through the improved cap, illustrating its application to a standard milk bottle.

Fig. 2 is a plan view thereof.

Fig. 3 is a fragmentary diagrammatic view illustrating the cap in its applied position but unlocked.

Fig. 4 is a similar view illustrating the cap in locked position.

Referring to the drawings by characters of reference, which denote like elements throughout the several views, A designates 60 the neck of a standard milk bottle having the usual enlarged external bead B. The bore of the neck is formed with the horizontal shoulder C constituting the seat for the usual form of cap and the portion D of 65 the bore lying between the shoulder C and the pouring lip E is frustoconical and of gradually decreasing diameters toward the outer end. The portion F of the bore which communicates with the neck proper is of 70 a gradually increasing diameter toward its lower end immediately adjacent the shoulder. The foregoing is a detailed description of the construction of the neck of a 75 standard milk bottle and forms no part of the present invention.

The cap constituting the invention and designed as a closure for a bottle of the foregoing outlined construction is preferably constructed of compressed paper, paste 80 board or any other suitable material containing the necessary qualities to perform the functions for which it is intended. The cap is pressed, molded, cast or otherwise formed of a piece of material to provide the 85 bore covering portion 10 and the pouring lip housing portion 11, the juncture of said portions being horizontally stepped to provide the horizontal and vertical annular sealing faces 12 and 13 and 14, adapted for 90 respective engagement with the horizontal shoulder C, and portions D and F of the bore. The internal diameter of the portions D and F of the bore are constant in all makes of bottles but there is a great variation 95 in the form and curvature of the pouring lip and the diameter of the external bead B. The pouring lip housing 11 is therefore made to accommodate the maximum size of pouring lip E and bead B. 100 The central bore covering portion 10 is provided with a concentric circular portion 15 formed by the score 16 which is longitudinally adjustable in the neck to respectively advance or retract the sealing faces 12, 13 105 and 14 into engagement with the shoulder C or the portion F of the bore. The pouring lip housing 11 and the bore covering portion 10 lying between the vertical sealing face 14 are provided respectively with 110

the strengthening ribs 17 and 18. The ribs 17 serve to impart sufficient resiliency to the pouring lip housing to set up a gripping and embracing action of the housing to seal 5 the extreme outer edge 19 against the outer edge of the bead B.

In practice and use of the cap, when the housing 11 is initially positioned over the pouring lip as illustrated in Fig. 3, the circular center portion 15 is raised to its uppermost limit, thereby effecting a slight radial retraction of the sealing faces 13 and 14 to allow for their insertion within their respective seats. When the cap is properly positioned, the center portion 15 is forced downward, as illustrated in Fig. 4, past the horizontal plane of the juncture of the bore covering portion to lock and retain the cap in place and the sealing faces in binding contact 20 with their respective seats. To remove the cap, it is first necessary to raise the center portion 15 to effect an unlocking of the sealing faces from their seats.

While there has been illustrated and described a single and preferred embodiment of the invention, no limitation is necessarily made to the precise structural details, as changes and modifications falling within the scope of the claims, may be resorted to 30 when desired.

Having thus described my invention, I claim as new and desire to secure by Letters Patent:

1. In a bottle cap, including a bore covering portion, and a pouring lip housing, the juncture therebetween being stepped to constitute a horizontal sealing face and outer vertical sealing peripheries adapted to respectively engage and co-act with the horizontal seat and the inclined bores of a milk bottle above and below said seat.

2. The combination with a milk bottle, provided with an external bead, a pouring lip, an internal horizontal seat, and downwardly and outwardly flared walls above and below said seat, of a cap including a central bore covering portion and an annular pouring lip housing formed at the periphery thereof, the juncture of said portion and housing being stepped to provide a horizon-

tal sealing face adapted to engage and co-act with the seat and superposed vertical sealing peripheries adapted to co-act respectively with the flared walls.

3. The combination with a milk bottle, 55 provided with an external bead, a pouring lip, an internal horizontal seat, and downwardly and outwardly flared walls above and below said seat, of a cap including a central bore covering portion and an annular 60 pouring lip housing formed at the periphery thereof, the juncture of said portion and housing being stepped to provide a horizontal sealing face adapted to engage and co-act with the seat and superposed vertical 65 sealing peripheries adapted to co-act respectively with the flared walls, said bore covering portion being concentrically scored to provide means for shifting the same to effect engagement and disengagement of the 70 sealing face and peripheries.

4. The combination with a bottle provided with a neck formed with a central bore, having a horizontal seat, frustoconical vertical walls immediately adjacent thereto, 75 one of which terminates in an outturned pouring lip, of a cap adapted to be associated therewith which comprises a central bore covering portion and an outer pouring lip housing, the juncture therebetween being 80 horizontally stepped to provide superposed vertical sealing faces and a horizontal sealing face connecting the same.

5. The combination with a bottle provided with a neck formed with a central 85 bore, having a horizontal seat, frustoconical vertical walls immediately adjacent thereto, one of which terminates in an outturned pouring lip, of a cap adapted to be associated therewith which comprises a central 90 bore covering portion and an outer pouring lip housing, the juncture therebetween being horizontally stepped to provide superposed vertical sealing faces and a horizontal sealing face connecting the same, the center 95 bore covering portion being axially shiftable to respectively effect engagement or disengagement of the sealing faces.

EWALD G. BAUM.
